UNITED STATES PATENT OFFICE.

ENOCH OHNSTRAND, OF SYRACUSE, NEW YORK, ASSIGNOR TO OLIVER M. EDWARDS,
OF SYRACUSE, NEW YORK.

SHEET-METAL FILING-BOX.

1,213,240.

Specification of Letters Patent.

Patented Jan. 23, 1917.

Application filed July 29, 1911. Serial No. 641,355.

To all whom it may concern:

Be it known that I, ENOCH OHNSTRAND, of 5
Syracuse, in the county of Onondaga and
State of New York, have invented a certain
new and useful Sheet-Metal Filing-Box, of
which the following is a specification.

This invention has for its object the pro-
duction of a sheet metal filing or index card
box, and it consists in the novel combinations
10 and constructions hereinafter set forth and
claimed.

In describing this invention reference is
had to the accompanying drawing in which
like characters designate corresponding
15 parts in all the views.

Figure 1 is a plan of a section of the box.
Figs. 2 and 3 are respectively vertical longi-
tudinal and cross sectional views. Fig. 4 is
a detail view of one of the face plates.

20 My invention is here shown as embodied in
a box composed of a central section and end
sections hinged thereto and movable into and
out of closed positions with respect to the
central section, each section being a box in
25 itself and having a guide for index or other
cards therein.

The central section comprises side and end
members or flanges 1, 2, and reversely ar-
30 ranged members 3 comprising bottoms ar-
ranged back to back and side flanges 4 inter-
locked with the side members 1, the bottoms
being also formed with corrugations 5 ar-
ranged about midway between and parallel
35 to the side members, the corrugations serv-
ing as guides for the cards filed in the box.
One set of the interlocking parts here shown
as the side members 1 are formed with in-
40 internal channels facing toward each other,
and the other set of interlocking parts as the
flanges 4 are provided with means fitting
said channels, Fig. 3. The end members 2
are also formed with internal channels simi-
45 lar to those of the side members 1, Fig. 2.
Preferably a metal sheet 6 is interposed be-
tween the bottoms of the members 3 and the
edges thereof abut against the inner mem-
50 bers 1 and 2. The central section also com-
prises reversely arranged face plates 7 ar-
ranged on opposite sides of the members 3,
said plates interlocking with the channels of
55 the end members 2 and having slots 8 for re-
ceiving the corrugations 5, Fig. 4.

The channels of the side and end members
1, 2 are preferably rectangular and the
55 flanges 4 of the members 3 have their mar-

gins bent at a right angle to the major part
of such flange, said margins 9 fitting the
channels of the side members 1, and the
edges thereof abutting against the sides 1.
The flanges 4 are also spaced apart from the 60
side members 1 and together therewith form
hollow walls. Preferably said corrugations
5 are also rectangular in form but obviously
may be of any other form.

As shown in Fig. 3, the upper and lower 65
margins 10 and 11 of the face plates 7 are
bent at a right angle to said plates and fit
into the channels of the end members 2, the
flanges 11 resting on the end margins of the
metal sheet 6, Fig. 2.

The side and end members or flanges 1, 2
and also the margins thereof forming the
internal channels are united at the corners
in any suitable manner as by welding.

70 The end sections or boxes are hinged re-
spectively at 12 and 13 to the central section
or box, and each end section comprises a
sheet metal body including a bottom 14 and
side and end flanges 15 and 16 usually in-
75 tegral with the bottom, and a sheet metal 80
member engaging the bottom 14 and having
flanges 17 interlocking with the side flanges
15 and a central rectangular corrugation or
guide 18 similar to the corrugation or
guide 5.

85 One set of interlocking flanges, here shown
as the side flanges 15, are formed with chan-
nels facing the bottom and the other, as the
flanges 17, are provided with means fitting
the bottoms of the channels. As here shown
90 the margins 19 of the side flanges 17 are bent
at a right angle to such flanges and coact
with channels of the sides in a manner simi-
lar to the margins 9 of the members 3 of the
central section.

95 Each of the end sections also comprises a
face plate 20 at each end thereof, such face
plate being similar to the face plate 7, and
coacting with the channel of each end mem-
ber and with the corrugation 18 in substan-
100 tially the same manner as the plates 7 coact
with the channels of the ends 2, and the cor-
rugation 5 of the central section.

105 In use the box can be opened so that one
compartment of the central section and one
of the two end sections are accessible. A box
constructed as described is particularly rigid
and durable and economically manufactured.

What I claim is:

110 1. A box comprising a substantially rec-

- 5   tangular body having a bottom, and sides having the marginal edges thereof bent to form channels facing said bottom, and a sheet metal member having an integral centrally disposed lengthwisely extending corrugation, bottom portions on opposite sides of the corrugations extending in parallelism with the bottom of the body, and sides spaced apart from the sides of the body and having angular marginal portions engaging the walls of the channels formed by the marginal portions of the sides of the body, substantially as and for the purpose specified.
- 10   6. A box comprising a sheet metal body having a bottom and sides integral with the bottom, the sides having their margins bent to form internal channels facing the bottom, and a sheet metal member engaging the bottom and formed with a raised guide located between the sides of the body, said member also having flanges at its opposite edges for entering said channels and snugly fitting the channels, substantially as and for the purpose set forth. 70
- 15   7. A box comprising a sheet metal body having a bottom and sides integral with the bottom, the sides having their margins bent to form internal channels facing the bottom, and a sheet metal member including a bottom engaging the bottom of the body and flanges at its opposite sides opposed to the first-mentioned flanges, the flanges on one of said parts being formed with channels facing the bottom and the flanges in the other of said parts extending into said channels, substantially as and for the purpose specified. 80
- 20   8. A box comprising a sheet metal body having a bottom and sides integral with the bottom, the sides having their margins bent to form internal channels facing the bottom, and a sheet metal member including a bottom engaging the bottom of the body, and flanges at its opposite sides opposed to and spaced apart from the sides of the body and together therewith forming hollow walls, the flanges interlocking with said channels, substantially as and for the purpose described. 85
- 25   9. A box comprising a sheet metal body having a bottom and sides integral with the bottom, the sides having their margins bent to form internal channels facing the bottom, and a sheet metal member including a bottom engaging the bottom of the body, and flanges at its opposite sides opposed to and spaced apart from the sides of the body and together therewith forming hollow walls, the flanges interlocking with said channels, and having their margins bent at an angle to engage the bottoms of said channels, the edges of the margins abutting against the inner faces of the sides, substantially as and for the purpose specified. 95
- 30   10. A box comprising a sheet metal body having a bottom and sides integral with the bottom, the sides having their margins bent to form internal rectangular channels facing the bottom, and a sheet metal member engaging the bottom and formed with a raised corrugation between the sides, said corrugation being rectangular in cross-section, and said member also having flanges at its opposite sides opposed to, and spaced apart from, the sides of the body and together therewith forming hollow walls, the flanges extending into the channels, and the margins thereof being bent at a right angle to the major portions thereof for fitting the bottoms of said rectangular channels, substantially as and for the purpose set forth. 100
- 35   11. A box comprising a sheet metal body having a bottom and sides integral with the bottom, the sides having their margins bent to form internal channels facing the bottom, and a sheet metal member including a bottom engaging the bottom of the body and flanges at its opposite sides extending into such channels and snugly fitting the channels, substantially as and for the purpose specified. 110
- 40   12. A box comprising a sheet metal body having a bottom and sides integral with the bottom, the sides having their margins bent to form internal rectangular channels facing the bottom, and a sheet metal member including a bottom engaging the bottom of the body, and flanges at its opposite sides opposed to, and spaced apart from, the sides of the body and together therewith forming hollow walls, the flanges extending into the channels, and the margins thereof being bent at a right angle to the major portions thereof for fitting the bottoms of said rectangular channels, substantially as and for the purpose set forth. 115
- 45   13. A box comprising a sheet metal body having a bottom and sides integral with the bottom, the sides having their margins bent to form internal channels facing the bottom, and a sheet metal member including a bottom engaging the bottom of the body and flanges at its opposite sides opposed to, and spaced apart from, the sides of the body and together therewith forming hollow walls, the flanges extending into the channels, and the margins thereof being bent at a right angle to the major portions thereof for fitting the bottoms of said rectangular channels, substantially as and for the purpose set forth. 120
- 50   14. A box comprising a sheet metal body having a bottom and sides integral with the bottom, the sides having their margins bent to form internal channels facing the bottom, and a sheet metal member including a bottom engaging the bottom of the body and flanges at its opposite sides opposed to, and spaced apart from, the sides of the body and together therewith forming hollow walls, the flanges extending into the channels, and the margins thereof being bent at a right angle to the major portions thereof for fitting the bottoms of said rectangular channels, substantially as and for the purpose set forth. 125
- 55   15. A box comprising a sheet metal body having a bottom and sides integral with the bottom, the sides having their margins bent to form internal channels facing the bottom, and a sheet metal member including a bottom engaging the bottom of the body and flanges at its opposite sides extending into such channels and snugly fitting the channels, substantially as and for the purpose specified. 130

5 having a bottom and sides and ends integral with the bottom, the sides and ends having their margins bent to form internal channels facing the bottom, a sheet metal member resting on the bottom and formed with a central corrugation and with flanges at its opposite sides interlocked in the channels of the sides, and face plates interlocked in the channels of the ends of the box and formed with slots for receiving said corrugation, substantially as and for the purpose set forth.

10 12. A box comprising a sheet metal body having a bottom and sides and ends integral with the bottom, the sides and ends having their margins bent to form internal rectangular channels facing the bottom, a member engaging the bottom and formed with a corrugation between the sides and 15 with flanges at its sides opposed to the sides of the body and together therewith forming hollow walls, the flanges having their margins bent at an angle for engaging the bottoms of the channels, and face plates at the 20 ends of the body the face plates having their margins farthest from the bottom bent at a right angle to the major part of such plates, and engaging the bottoms of the channels of the ends, the face plates also having slots for 25 receiving the corrugation, substantially as and for the purpose described.

30 13. A box comprising a central section, and upper and lower sections movable into and out of closed positions with respect to the central section, the central section comprising side members, and reversely arranged members having sheet metal bottoms arranged back to back and side flanges for 35 interlocking with the side members, one set of such interlocking parts being provided with channels facing toward each other and toward the bottoms, and the other set of interlocking parts having means fitting the channels, substantially as and for the purpose specified.

40 14. A box comprising a central section, and upper and lower sections movable into and out of closed positions with respect to the central section, the central section comprising side members, and reversely arranged sheet metal members having bottoms arranged back to back and side flanges for interlocking with said side members, the bottoms being formed with card guides 45 consisting of corrugations parallel to the side flanges and one set of the interlocking parts being formed with channels facing toward each other and toward the bottoms and the other set of interlocking parts extending 50 into such channels, substantially as and for the purpose set forth.

55 15. A box comprising a central section, and upper and lower sections movable into and out of closed positions with respect to the central section, the central section com-

60 prising side members, and reversely arranged sheet metal members having bottoms arranged back to back and side flanges for interlocking with said side members, the bottoms being formed with card guides consisting of corrugations parallel to the side flanges and one set of said interlocking parts being formed with channels facing toward each other and toward the bottoms and the other set of interlocking parts extending 65 into such channels, and a metal sheet interposed between said bottoms and engaging the same, the edges of the sheet engaging the inner faces of the sides and ends of such section, substantially as and for the purpose described.

70 16. A box comprising a central section, and upper and lower sections movable into and out of closed positions with respect to the central section, the central section comprising side members formed with internal channels facing toward each other, and reversely arranged sheet metal members having bottoms arranged back to back and side flanges for interlocking with said channels, 75 substantially as and for the purpose specified.

80 17. A box comprising a central section, and upper and lower sections movable into and out of closed positions with respect to the central section, the central section comprising side members formed with internal channels facing toward each other, and reversely arranged sheet metal members having bottoms arranged back to back and side flanges for interlocking with said channels, 85 the bottoms being formed with corrugations arranged parallel to the side flanges, substantially as and for the purpose set forth.

90 18. A box comprising a central section, and upper and lower sections movable into and out of closed positions with respect to the central section, the central section comprising side members, each formed with internal channels facing toward each other, and reversely arranged sheet metal members 95 having bottoms arranged back to back and side flanges for interlocking with said channels, the bottoms being formed with corrugations arranged between the sides, and a metal sheet interposed between said bottoms 100 and engaging the same, the edges of the sheet engaging the inner faces of the sides and ends of said section, substantially as and for the purpose described.

105 19. A box comprising a central section, 110 and upper and lower sections movable into and out of closed positions with respect to the central sections, the central section comprising side and end members, each formed with internal channels at their opposite margins facing toward each other, reversely arranged sheet metal members arranged back to back and having side flanges interlocking with the channels of the side members of the central section, said members being also 115 120 125 130

provided with corrugations extending parallel to the flanges, and a pair of reversely arranged face plates at each end of said section, the face plates having slots for receiving the corrugations respectively, said plates having their margins farthest removed from said members bent to fit the bottoms of the channels of the end members, substantially as and for the purpose specified.

20. A box comprising a central section, and upper and lower sections movable into and out of closed positions with respect to the central section, the central section comprising side and end members, each formed with internal channels at their opposite margins facing toward each other, reversely arranged sheet metal members having their bottoms arranged back to back and having side flanges interlocking with the channels of the side members of the central sections, the bottoms being formed with corrugations extending parallel to the side flanges, a pair of reversely arranged face plates at each end of said section, the face plates having slots for receiving the corrugations respectively, and having their margins farthest removed from the bottoms bent to fit the bottoms of said channels, and a metal sheet interposed between the bottoms of the reversely arranged members and engaging at its side and end edges with the inner faces of the side and end members, substantially as and for the purpose set forth.

21. A box comprising a central section, and upper and lower sections movable into and out of closed positions with respect to

the central section, the central section comprising side and end members, each formed with internal channels facing toward each other, reversely arranged sheet metal members having bottoms arranged back to back and side flanges interlocking with said channels, each bottom being formed with a central corrugation arranged parallel to the side flanges, and a pair of reversely arranged face plates at each end of the central section, the face plates having slots for receiving the corrugations and having their margins farthest removed from the bottoms bent to fit the bottoms of the channels of the end members, and the end sections being hinged to the central section, and each comprising a sheet metal body having a bottom and sides and ends integral with the bottoms, each side and end having its margin bent to form internal channels facing the bottom of such end section, and a sheet metal member engaging the bottom and having flanges at its sides extending into the channels of such end section and interlocking therewith, each end section also having face plates at its ends arranged similarly to the first-mentioned face plates, substantially as and for the purpose described.

In testimony whereof, I have hereunto signed my name in the presence of two attesting witnesses, at Syracuse, in the county of Onondaga, in the State of New York, this 27th day of July, 1911.

ENOC OHNSTRAND.
